UNITED STATES PATENT OFFICE

SAMUEL MCEWEN, OF LONDON, ENGLAND, ASSIGNOR TO COAL OIL EXTRACTIO
LIMITED, MANUFACTURERS, OF LONDON, ENGLAND

APPARATUS FOR CARBONIZING OR DISTILLING MATERIALS

Application filed July 11, 1929, Serial No. 377,372, and in Great Britain June 8, 1928.

For the purpose of causing or facilitating the travel through a retort of the material to be carbonized or distilled, it has been proposed to provide the retort with a movable wall or a part of a wall which is given a reciprocating movement, and in some cases it has been proposed to construct such movable wall in such a manner that it permits escape of volatile products through it.

According to the present invention a wall of a carbonizing or distilling retort is formed by an endless band or articulated chain grate passing over rollers, or a wall of the retort may be made up of fixed wall sections and one or more such bands or chain grates. In another form the upper part of a vertical or inclined retort may be of usual construction and a lower part of a wall may be constructed of the moving band or grate. Volatile products are preferably withdrawn from the retort through the band or grate.

In the case where the band or grate has reciprocating movement the upward stroke would not necessarily move the material because of the head of material above, aided by gravity; however, additional resistance may be provided if movement by the upward stroke is undesirable.

In the case of a horizontal retort the band or chain grate may constitute a side or the top or bottom of the retort, or a part thereof.

A bench of retorts, each of rectangular cross section, may be constructed of fixed walls, containing heating flues, alternating with pairs of endless bands or chain grates, travelling continuously or intermittently. Alternatively, a single endless band or chain grate, may be used between the fixed walls, but in the case of vertical retorts the grate must then be given a reciprocating movement. The spaces between the travelling bands and the fixed walls receive the material. The construction may be such that the distance between the travelling band and the fixed wall is adjustable, and when it is desirable that the moving wall and the fixed wall should be at an angle to each other, the magnitude of this angle may be adjustable.

When it is desirable that the products formed in the different zones of the retort

should be kept separate, compartments may be constructed behind the chain grate in such a manner that from each compartment may be withdrawn the products formed in the corresponding zone.

The accompanying drawing illustrates the invention. Fig. 1 is a diagrammatic vertical section through a bench of vertical retorts constructed according to the modification in which one wall of the retort is constituted by one of the runs of a continuously travelling grate, similar in general construction to a travelling grate stoker. Fig. 2 is a like view of a modification.

The bench is composed of pairs of such grates *a* alternating with walls *b*. The grates run on driven sprocket drums *c* and idle drums *d*; they are suitably supported against lateral pressure by guides *e*. The details of the construction will be obvious to those skilled in the art of chain grate stokers, since the grates here shown are similar to such stokers, but operate in a vertical plane instead of in a horizontal plane. They are provided with projections *f* intended to engage to some extent the coal which is charged from a hopper *g* and slides down the inclined planes *h* into spaces between the walls *b* and the grates *a*. These spaces constitute the retorts, the coal being heated to a temperature suitable for low temperature carbonization by passage of combustion gases through the flues indicated in the walls *b*.

The particular construction of flues here illustrated is as follows:—*i* is a furnace chamber fed by a gas burner inserted at *k*. The products of combustion take a zig-zag course through flues *l*, *m* and *n* and so on, finally escaping through outlet *o*. Thus the main heating is in the lower part of the retort. At the zone at the level of the flue *n* passages *p* in the wall receive steam which becomes superheated by the gases in the flue and issues through ports *q* into the retort.

The space between the runs of the endless grate is subdivided by horizontal baffles *r* and these, together with the side plates *s* and the plates *t* which are behind the idle run of the grate *a*, form a number of chambers into which the volatile products of carbonization

escape freely through the grate. These products are withdrawn from each chamber by suction applied at the openings *u* and may be collected separately, if desired.

5 Owing to the aid afforded to gravity by the chain grate it is not generally necessary that there should be any taper in the walls of the retort, but provision is made for adjusting the bearings *v* of the idle drum *d* of 10 the chain grate so that the latter may be slightly inclined to the wall *b* when it is desired that the capacity of the retort shall increase somewhat in the downward direction.

15 The carbonized coal is discharged into hoppers *w* from which it is withdrawn by an airtight delivering device in known manner.

20 Referring to Fig. 2, the passages for withdrawal of volatile products through the openings *u* are provided with valves which can be closed, and there is a pipe *y* in communication with the hopper *w* which receives the hot coke discharged from the retorts.

25 Through this pipe *y* the volatile products of the carbonization are withdrawn, that is to say the vapours and gases are drawn downwards from the retorts so that they pass through the hot coke in the lower part thereof and in the hopper *w*, leaving the latter by the pipe *y*.

30 The retort is adapted either for the mode of operation described with reference to Fig. 1 or as just described, there being a valve (not shown) in pipe *y* which is closed when the passages connected with openings *u* are open 35 for the first mode of operation.

Having thus described the nature of the said invention and the best means I know of carrying the same into practical effect, I claim:—

40 1. In a carbonization retort, a stationary heating wall, an endless chain grate conveyor, one run of which is substantially parallel to and spaced from said heating wall to provide a carbonization space, steam channels in the 45 side of said heating wall which faces said chain grate, ports in said side of the heating wall communicating with the steam channels and with said carbonization space, a gas collecting chamber on the side of said run remote from the heating wall, and means for conveying gas through said run from the carbonization space to said gas collecting chamber.

50 2. In a carbonization retort, a stationary heating wall, an endless chain grate conveyor, 55 one run of which is substantially parallel to and spaced from said heating wall to provide a carbonization space, steam channels in the side of the heating wall which faces said chain grate, ports in said side of the heating 60 wall communicating with said steam channels and with the carbonization space, and means for separately taking off gas from different portions of said space comprising gas collecting chambers and means for separately conveying gas from different portions of said

space to said gas collecting chambers respectively.

3. In a carbonization apparatus, the combination of a heating wall, a pair of chain grate conveyors on opposite sides of said wall, one run of each of said conveyors being substantially parallel to and spaced from said wall so as to provide carbonization spaces, steam channels in the opposite sides of said wall, ports in the sides of the wall communicating with the steam channels and with said spaces, gas collecting chambers, one on the side of each run remote from said heating wall, and means for conveying gas through said runs from said carbonization spaces to said collecting chambers.

4. In a carbonization apparatus, the combination of a heating wall, a pair of chain grate conveyors on opposite sides of said wall, one run of each of said conveyors being substantially parallel to and spaced from said wall so as to provide carbonization spaces, steam channels in the opposite sides of said wall, ports in the sides of the wall communicating with the steam channels and with said spaces, and means for separately taking off gas from different portions of each of said spaces, comprising gas collecting chambers and means for separately conveying gas from different portions of each of said spaces to said gas collecting chambers respectively.

In testimony whereof I have signed my name to this specification.

SAMUEL McEWEN.
